ABSTRACT: A mop includes a handle and a sleeve member which caps one end portion of the handle. A mophead includes a holder member for mopping material and the holder member is provided with a recess so dimensioned as to accommodate the sleeve member therein. Friction-promoting projections are provided on the exterior of the sleeve member or in the interior of the recess so as to establish a releasable frictional connection between the sleeve member and the holder member when the former is inserted into the recess of the latter. Rotation-preventing means is provided for preventing relative rotation of the members when the mop is in use.

ATTORNEY

MOP

BACKGROUND OF THE INVENTION

The present invention relates generally to cleaning implements, and more particularly to a mop.

Mops of many types and descriptions are well known. They are all satisfactory in some respects and unsatisfactory in others. They all, however, have one feature in common: namely the fact that the mop handle generally outlasts the mophead—which latter may consist of string, strips of synthetic plastic foam material, or the like—must be periodically replaced. This, on the other hand, necessitates that the mophead be releasably connected with the handle.

It is in this respect that prior-art mops are generally most disadvantageous. The connection between the mop handle and the mophead should on the one hand be firm and not subject to accidental or undesired separation while, on the other hand, it should be readily separable when necessary. Conventionally such connection is effected by providing the holder which constitutes a part of the mophead and on which the mopping material is secured, with an internally threaded recess whereas the end portion of the mop handle is exteriorly threaded and the two threads are brought into mesh. With this type of connection, it is a common complaint, however, that because of the frictional resistance encountered by the mop in use, particularly if a wet mop is concerned, the connection will soon loosen because of the rotational forces acting upon the mophead in use, so that the connection must be constantly retightened to prevent the mophead from becoming separated from the mop handle.

A further problem exists in the manner in which the mopping material is connected with the holder of the mophead. This connection should advantageously be very simple, not only to facilitate assembly of the mopping material with holder during the manufacture of the mop, but also to provide later on the possibility of replacing only the mopping material while retaining the holder, this type of replacement being obviously less expensive than if both the mopping material and the holder must be replaced simultaneously for which there is usually no need because the holder generally will outlast the mopping material.

SUMMARY OF THE INVENTION

It is therefore a general object of the present invention to provide a novel mop having the aforementioned desirable features.

An additional object of the present invention is to provide a mop wherein the mophead may be readily and conveniently releasably connected with the mop handle.

A further object of the invention is to provide such a mop wherein the mopping material may be readily and releasably but yet firmly connected with the holder constituting a part of the mophead.

A concomitant object of the present invention is to provide a mop having a releasable connection between the mophead and the mop handle which nevertheless reliably prevents turning movement of one with reference to the other in use of the mop.

An additional object of the present invention is to provide such a mop which is inexpensive to manufacture and very simple to assemble.

In pursuance of the above objects, and others which will become apparent hereafter, one feature of my invention resides in the provision of a mop including a handle and a sleeve member which caps one end portion of the handle. A mophead is provided which includes mopping material such as strings, ropes, threads, strips or the like of suitable material, and a holder member for the mopping material, and in accordance with the invention the member is provided with a recess so dimensioned as to accommodate the sleeve member therein. Friction-promoting means is provided on at least one of the members whereby to establish a releasable frictional

connection of the sleeve member with the holder member in response to introduction of the former into the recess of the latter. Finally I provide rotation-preventing means which is also present on at least one of the members for preventing 5 relative rotation of the members when the mop is in use.

Advantageously one or both of my sleeve member and holder member consist of synthetic plastic material, among which I wish to mention polyethylene and polypropylene as two exemplary suitable materials.

10 The friction-promoting means may be provided on the external surface of the sleeve member, and the internal surface bounding the recess in the holder member, or on both surfaces and may take the form of projections, preferably ribs or ridges extending in longitudinal direction of the recess.

15 As far as my rotation-preventing means is concerned, this may also be provided in the form of projecting portions or the like. The perhaps simplest solution is to make the cross-sectional configuration of the exterior of the sleeve member and the interior of the recess of the holder member of other-than-circular outline, for example of polygonal outline, which necessarily precludes rotation of one member with reference to the other when the sleeve member is received in the recess of the holder member.

20 The novel features which are considered as characteristic for the invention are set forth in particular in the appended claims. The invention itself, however, both as to its construction and its method of operation, together with additional objects and advantages thereof, will be best understood from the following description of specific embodiments when read in connection with the accompanying drawing.

BRIEF DESCRIPTION OF THE DRAWING

FIG. 1 is an axial section of a mop according to my invention, with the handle being shown fragmentarily;

FIG. 2 is a view in direction of the arrows II—II in FIG. 1; and

40 FIG. 3 is a section taken on the line III—III of FIG. 1 as seen in the direction of the arrows associated with the sectioned line.

DESCRIPTION OF THE PREFERRED EMBODIMENTS

Discussing now the illustrated embodiment in more detail it will be seen that I provide a conventional mop handle 1 which will usually consist of wood but which may also consist of metallic material, for instance aluminum for the sake of light weight, or a synthetic plastic material. A sleeve member 2 caps one end portion of the handle 1, that is the sleeve member 2 is provided with a bore or hollow in which the end portion of the handle 1 is received as illustrated. Any suitable means may be employed for rigidly connecting the sleeve member 2 with the end portion of the handle 1, for instance one or more nails, screws or the like may be driven through the wall of the sleeve member 2 into the end portion of the handle 1, and adhesive connection may be effected, or another suitable expedient may be employed.

In the illustrated embodiment the outer cross-sectional configuration of the sleeve member 2 is polygonal, as clearly shown in FIG. 3.

I further provide a mophead including mopping material 10 and a holder member 3 holding the mopping material arranged to be connected with the sleeve member 2. As shown in FIG. 1, the holder member 3 includes a first body portions 65 3a and a second body portion 3b which will usually be integral with one another, that is be made of one piece with one another. I prefer to make the members 2 and 3 from synthetic plastic material in which case they may be injection-molded or manufactured in another suitable manner. The portion 3a of the member 3 is provided with a recess 4 having, as most clearly visible in FIG. 3, an interior cross-sectional configuration which is polygonal and corresponds to the exterior cross-sectional configuration of the member 2 which latter is thus readily accommodated in the recess 4 because the same is dimensioned accordingly.

Friction-promoting means is provided on at least one of the members 2 and 3, and is here illustrated as a plurality of raised ridges 4a provided on the inner circumferential surface bounding the recess 4 and extending axially of the latter. On introduction of the sleeve member 2 into the recess 4, frictional contact with the ridges 4a maintains the sleeve member 2 tightly but yet readily releasably positioned within the recess 4. Advantageously, although not necessarily, I will border the inlet opening of the recess 4 with guide faces 4b converging in direction inwardly into the recess 4 and serving to more readily introduce the sleeve member 2 into the recess 4.

In this embodiment the rotation-preventing means is provided by making the outer cross section of sleeve 2, and the inner cross section of recess 4, polygonal as shown in FIG. 3. The portion 3b, on the other hand, is also provided with a depression 5 having an open side facing away from the recess 4, as illustrated in FIG. 1. A plurality of circumferentially spaced mounting or retaining projections 7 which may be solid or tubular in form, project from the bottom wall 6 bounding the recess 5 towards the open side of the latter. A plate member 8, which may consist of metallic material, but could also be made of another material such as a synthetic plastic, is provided with a plurality of apertures 9 therein which correspond in number and arrangement to the number and arrangement of the retaining projections 7. The apertures 9 are so dimensioned that when one of the retaining projections 7 is introduced thereto, it will be tightly retained so that, when the plate member 8 is introduced through the open side of the recess 5 so that all of the retaining projections 7 can enter into the respectively associated apertures 9, the plate member 8 will be tightly but yet releasably retained in the recess 5. Connection of the mopping material, here illustrated as threads, strings or the like, is effected by having portions of the mopping material extend into the recess 5 and be clamped between the plate member 8 and the bottom wall 6 bounding the recess 5. It will be noted that the outer diameter of the plate member 8 is somewhat smaller than the inner diameter of the recess 5 so that an annular gap exists between the edge of the plate member 8 and the inner surface bounding the recess 5, through which gap the major portions of the mopping material 10 extend outwardly of the recess 5, as somewhat diagrammatically illustrated in FIG. 1.

Finally, I may provide reinforcing means for reinforcing the wall of the portion 3a at least in the region of the inlet opening to the recess 4. In the illustrated embodiment I have shown this in FIG. 1 in the form of an annulus 11 of metallic material which is embedded in the wall of the portion 3a of the holder member 3 adjacent the inlet opening to the recess 4. This prevents yielding of the material of the member 3, which may be a problem if certain types of plastic material are used for making the member 3 and which could occur in use of the mop, thus permitting the member 3 to become undesirably separated from the member 2. It will be appreciated that the annulus 11 will be embedded at the time of manufacture of the member 3, but that it could also conceivably be added at a later date in which case it would have to be of such type as to either surround the portion 3a externally thereof, or to be located in a recess provided in either the inner or outer circumferential face of the portion 3a.

It will be understood that each of the elements described above, or two or more together, may also find a useful application in other types of constructions differing from the types

described above.

While the invention has been illustrated and described as embodied in a mop, it is not intended to be limited to the details shown, since various modifications and structural changes may be made without departing in any way from the spirit of the present invention.

What is claimed as new and desired to be protected by Letters Patent is set forth in the appended:

1. A mop, comprising in combination, a handle having an end portion; a sleeve member capping said end portion of said handle and having a polygonal outer cross-sectional configuration; a mophead including mopping material and a holder member for said mopping material, said holder member being provided with a recess of polygonal cross-sectional interior configuration and which accommodates said sleeve member therein so as to prevent relative rotation of said members when said mop is in use; and friction-promoting means provided on at least one of said members whereby to establish a releasable frictional connection of said sleeve member with said holder member in response to introduction of the former into said recess of the latter.
2. A mop as defined in claim 1, wherein said sleeve member and said holder member both consist at least in part of synthetic plastic material.
3. A mop as defined in claim 1, said recess being bounded by an inner circumferential surface; and wherein said friction-promoting means comprises a plurality of projections provided on said surface extending into said recess and frictionally engaging said sleeve member on introduction of the latter with said recess.
4. A mop as defined in claim 3, said projections comprising a plurality of circumferentially spaced elongated ribs.
5. A mop as defined in claim 1, said recess having an inlet opening for insertion of said sleeve member therein; and further comprising a plurality of guide surfaces provided at said opening bounding the same and converging in direction into said recess so as to guide said sleeve member into the same.
6. A mop as defined in claim 1, said recess having an inlet opening and at least said holder member being made of synthetic plastic material; and further comprising metallic reinforcing means embedded in said synthetic plastic material of said reinforcing member and surrounding said inlet opening of said recess.
7. A mop as defined in claim 1, said holder member including a first body portion provided with said recess and a second body portion provided with a depression in which said mopping material is partly received; and said mophead further including mounting means mounting said mopping material in said depression and connecting the mopping material with said holder member.
8. A mop as defined in claim 7, said depression having an open side and a bottom wall; and further comprising a plurality of angularly spaced retaining projections extending from said bottom wall toward said open side, and a plate member provided with a corresponding plurality of apertures each accommodating frictionally one of said retaining projections whereby portions of said mopping material located in said depression are tightly clamped between said plate member and said second body portion of said holder member.
9. A mop as defined in claim 8, wherein said plate member consists of metallic material.
